UNITED STATES PATENT OFFICE.

LEE DE FOREST, OF NEW YORK, AND JOHN LOUIS REYNOLDS, OF ASTORIA, NEW YORK,
ASSIGNORS, BY MESNE ASSIGNMENTS, TO GENERAL TALKING PICTURES CORPORATION,
A CORPORATION OF DELAWARE.

ACOUSTIC APPARATUS.

Application filed June 30, 1926. Serial No. 119,777.

This invention relates to improvements in sound reproducing apparatus used in connection with auditoriums and the like.

One of the objects of this invention is the improvement in the circuits used in connection with sound reproducing devices whereby any sound reproduction may be varied or adapted at will to the acoustic requirements of an auditorium.

10 Another object of this invention is the provision of a combination of apparatus for providing voice and musical productions in auditoriums in connection with the projection of a motion picture film.

15 A still further object of the invention is the combination of a motion picture projection machine and a phonofilm attachment with means for varying the sound reproductions in accordance with the character of the 20 sound being produced in order to adapt it for use with the auditorium.

These and many other objects are successfully sought by this invention as will appear hereinafter.

25 This invention resides substantially in the construction, arrangement, combination and relative location of parts and circuit assemblies, as will be clearly described below.

30 Referring to the drawings in which the preferred embodiments of my invention are disclosed; Figure 1 represents in diagrammatic form the general arrangement of the elements of our invention.

35 Figure 2 is a diagrammatic showing of the circuits used in connection with a modification of our invention.

40 Our invention relates particularly to the combination of an amplifier and sound reproducing device for theatre work, where the amplifier is advantageously located in the projection booth of the motion picture theatre and the loud speaker is located near the projection screen in the auditorium, and at some distance from the motion picture projection booth. We find that in auditoriums 45 of different sizes and arrangements, the acoustic requirements to give the best reproductions of sound must vary with the auditorium.

50 For example, if the auditorium is large and the walls are hard and undraped, the lower pitched tones from the horn being naturally of greater volume than the higher pitched tones produce in frequent instances, overpowering echoes which render it difficult for

people located at distances from the horns 55 to clearly understand. In such cases, it is important to reduce the volume of the reproduction in certain passages of the sound record to a greater degree than at other times. For example, when an orchestral number 60 (musical) is being reproduced the deep tones add richness and beauty to the record and it is possible under such circumstances that the low pitched tones may be reproduced to advantage in full volume; whereas, in a 65 speaking number where it is important that every word be clearly understood, we find that it is advantageous to reduce the sound volume during such passages and particularly the volume of the low pitched sounds.

70 Inasmuch as it is impossible for the operator in the projection booth to clearly hear what is going on from the horns at the other end of the auditorium due to the loud noises inseparable from the operation of the projection machine, it is highly desirable that the controlling means for regulating at will the sound volume be located in the auditorium at a distance from the projection booth. Such an arrangement is shown in Figure 1, where 75 1 represents the walls of the projection booth containing the projection machine, 3, equipped with the phonofilm reproducing attachment 4, such as described in the co-pending application of Lee de Forest, Serial 80 No. 635,334, filed April 28th, 1923, connected to the amplifier 5 and projecting the picture through the window 2 in the wall of the projection booth, upon the screen 10 located at the other end of the auditorium. The loud 85 speaker horn 9 is shown in this case located underneath the screen 10 and is connected to the output of the amplifier 5 by means of the walls 6 in one of which is included the variable resistance 8.

90 By means of the arrangement here shown, some competent person located in the auditorium, as for example, the orchestra conductor has it within his power to readily control at will the volume of the sound reproduction to suit the acoustic requirements of that particular auditorium and to modulate the particular number which is being reproduced to give the best and most intelligible results.

100 By the arrangement shown in Figure 1, however, it is only possible to reduce all sound frequencies alike without discrimina-

tion. It is highly desirable in addition to this to amplify at will the higher frequencies of a sound record or to diminish the volume of the lower frequencies without at the same time diminishing that of the higher frequency sound.

An arrangement for doing this is shown in Figure 2, in the two stage amplifier circuit. In this figure, 20 is the photo-electric cell into which the light from the photographic sound record is projected. This cell is energized by means of the battery 21 and the two in series are coupled to the input circuit of the vacuum tube 26 by means of the input resistance 22. 10 A condenser 23 is inserted in the lead to the grid and a high resistance grid lead 24 in series with the C or biasing battery 25 is shunted across the grid and film of the vacuum tube 26. The output of this tube is connected 15 through the primary 31 of a transformer and a battery 34. Connected across the terminals of the primary 31 is an inductance 28 having connected in one lead thereof the variable resistance 30. The variable capacitance 29 is shunted across the inductance 28. 20 The secondary 32 of the transformer is bridged by means of the potentiometer 33. A lead from one terminal of the secondary is connected through the condenser 35 to one 25 of the film leads. The grid circuit of the vacuum tube 27 is connected to the potentiometer 33 by means of the adjustable connection 40. The output or plate circuit of the tube 27 is connected through the coils 36 of 30 the sound reproducing device 10 and the plate battery 38. The filament battery 37 supplies the energy for lighting the filaments of the tubes.

The circuit interposed between the two tubes including the inductance 28, the capacitance 29 and the resistance 30 is known as an equalizer circuit. The function of the equalizer circuit is to shunt off from the input circuit of the three-electrode tube 27 to a greater 40 or less degree the lower frequency currents from the output of the three electrode tube 26. The relative amount of low frequency as against high frequency currents, which is thus shunted can be regulated by varying 45 either one of the three elements in the equalizer circuit, but preferably by varying the capacitance 29 or the resistance 30. By means of such an arrangement, it is possible for the operator at will to by-pass practically 50 all the lower frequency tones and to amplify only the higher frequencies or vice-versa, so that very wide range in sound timbre or quality of sound given out by the loud speaker can be obtained.

60 We find that in large auditoriums it is advantageous to reduce the volume of low frequency tones relative to those of the high frequency, whereas in smaller auditoriums, particularly where the walls, seats and other 65 fittings are draped and upholstered, and

where the echoes are less pronounced, it is possible to introduce more of the low frequency tones without harmful interference. Consequently, we find that such a circuit arrangement as just described is highly desirable in equipping the sound reproducing apparatus in various types of auditoriums. 70

Inasmuch as it is highly desirable that the sound equalizer system of the amplifier be actually embodied in the same, and that ordinarily this amplifier is located in the projection booth where it is very difficult or impractical for the operator to clearly hear or judge the sound reproduction in the auditorium, we prefer to adjust the equalizer circuit once 75 for all to best adapt the tonal qualities of the sound to that particular auditorium and not to vary the elements of the equalizer from time to time as this or that sound record is reproduced. However, we do not wish to be 80 limited in this respect, for it is perfectly feasible to install the amplifier or part of it down in the auditorium where the musical conductor or other expert can at will vary the control elements and thus emphasize to a 85 greater or less degree the high or tonal qualities of the sound from the loud speaker. 90

Instead of the equalizer system as shown in Figure 2, other equivalent arrangements well known in the art may be used. For example, 95 an equalizer system may be inserted in series between the photo-electric cell and the input of the first audion amplifier, or it may be inserted in series rather than in shunt between any two audion tubes of the amplifier series, 100 or the equalizer may be inserted directly in the output circuit of the last audion tube of the amplifier series. In this latter case, it is, of course, easy to locate the same in the auditorium in place of the simple rheostat as 105 shown in Figure 1. We find, however, that there are many advantages in inserting the equalizer system interstage in the amplifier as shown in Figure 2.

We have found in actual practise that with 110 any type of photo-electric cell containing gas there is a certain time lag or delay in operation to full sensitivity of the cell, which lag operates to reduce the relative strength of response to high frequency light variations 115 compared to that of low frequency light variations. For example, when the film record of a sound of 3,000 to 4,000 vibrations per second passes in front of the slit, thus cutting off or reducing the light which falls upon the photo-electric cell, 3000 to 4000 times per second, the relative apparent changes in resistance of the cell are far less pronounced, than when this same film is run in front of the slit at a 120 much slower speed, so that the light fluctuations fall upon the cell at the rate of say 500 to 1500 vibrations per second. This apparent loss in sensitivity of the photo-electric cell for high frequency light fluctuations may be 125 a phenomena peculiar to the small intensities 130

of light obtained when we employ such a short or narrow slit as is necessary with the phono-film device, but without going further into the theory or exact explanation of this observed 5 phenomena, the fact remains that there is an apparent lag in gaseous photoelectric cells to high frequency light fluctuations.

We have discovered the above effect, which was not recognized heretofore by authorities 10 on the photoelectric cell, and we have discovered a practical method of neutralizing this apparent cell lag or of compensating for same, by utilizing the equalizer circuit as described herein. By this method, the amplifier is made 15 to over-amplify the higher frequencies or under amplify the lower frequencies to a degree approximately inversely proportioned to the relative loss in sensitivity of the photo-electric cell with increased frequencies, as above 20 described.

We, therefore, desire and intend to cover the function of compensating for the time lag of the photo-electric cell, as well as adapting the sound reproducing device to the acoustic 25 requirements of any given auditorium. We are well aware of the fact that many changes in the details of construction and relative arrangement of parts may readily occur to those who are skilled in this art, and we do 30 not, therefore, desire to be strictly limited to the particular illustrative embodiment shown and described by us, but rather do we desire to be limited only by the appended claims.

What we seek to secure by United States 35 Letters Patent is:

1. In a sound reproducing system, the combination of an amplifier, a loud-speaker connected therewith, an auditorium containing said loud-speaker, and means controllable at 40 will for adapting the sound output from said loud-speaker to the acoustic requirements of said auditorium, said means including an equalizer circuit in said amplifier circuit, adapted to vary at will the relative intensities 45 of low and high frequency currents amplified in said amplifier.

2. In a sound reproducing system, the combination of an amplifier, a loud-speaker connected therewith, an auditorium containing said loud-speaker, and means controllable at 50 will for adapting the sound output from said loud-speaker to the acoustic requirements of said auditorium, said means including an equalizer circuit in said amplifier circuit, adapted to vary at will the relative intensities 55 of low and high frequency currents amplified in said amplifier, for the purpose of adapting the sound output from the loud-speaker to the acoustic requirements of said auditorium.

3. In a sound reproducing system, the combination of a photographic sound record, a photo-electric cell influenced by said sound record, a vacuum tube amplifier having a loud speaker connected thereto, and an auditorium containing said loud speaker, said amplifier 60 circuit including as an element thereof, an equalizer circuit adapted to amplify certain of the frequencies of a sound reproduction.

4. In a sound reproducing system, the combination of a photographic sound record, a photo-electric cell influenced by said sound record, a vacuum tube amplifier having a loud speaker connected thereto and an auditorium containing said loud-speaker, said amplifier 70 circuit including as an element thereof, 75 an equalizer circuit adapted to vary the volume of the high frequency sounds without correspondingly varying the lower frequency sounds of any sound reproduction.

5. The method of adapting a sound reproduction to the acoustic requirements of a given space which comprises changing light vibrations including a range of frequencies to sound vibrations and controlling the sound vibrations at will by increasing the volume of the high frequency sounds without correspondingly varying the low frequency sounds.

In testimony whereof we have hereunto set our hands on this 1st day of June, A. D. 1926.
